UNITED STATES PATENT OFFICE

CHARLES WALKER, OF KNOXVILLE, TENNESSEE

MULTIPLE VENDING MACHINE

Application filed September 29, 1930. Serial No. 485,168.

My invention consists in new and useful improvements in a coin controlled multiple vending machine and has for its object to provide a device of this character having mechanism adapted to vend any desired number of articles in a single operation when a coin or coins of different denominations are inserted.

Another object of my invention is to provide a vending machine of this type, having a minimum number of parts, and one which is simple in construction and operation as well as economical to manufacture.

With the above and other objects in view which will appear as the description proceeds, my invention consists in the novel features herein set forth, illustrated in the accompanying drawing, and more particularly pointed out in the appended claims.

Referring to the drawings in which numerals of like character designate similar parts throughout the several views,

Fig. 1 is a view in front elevation partially broken away and with the face of the housing removed to illustrate the internal mechanism.

Fig. 2 is a top plan view of the internal mechanism partially broken away.

Fig. 3 is a fragmentary view taken at right angles to Fig. 1 showing the delivery chamber and mechanism, and

Fig. 4 is a sectional view taken on line 4—4 of Fig. 3.

In the drawings, 1 represents the housing or container of my improved vending machine, one end wall of which is apertured and provided with a bearing or the like 2 adapted to rotatably support one end of a horizontal shaft 3, the other end of which terminates within the housing and is supported by a bearing 4 carried by a rigid vertical post 5 extending upwardly from the base of the housing. At predetermined

points on the shaft 3 I arrange a plurality of drums 6, 7 and 8 keyed or otherwise rigidly secured to the shaft 3 in spaced relation, each of said drums having an arcuate slot or recess 6', 7', and 8' respectively, arranged transversely in the upper side of its periphery as shown in Figs. 1 and 2. Although any

number of drums may be employed on the shaft 3, I have only shown three in order to avoid confusion.

The slots above mentioned are of a suitable size to receive a predetermined portion of various denomination of coins and are arranged in direct alignment with and adapted to receive coins from respective coin chutes 10, 11 and 12. For example, the chute 10 and slot 6' are of a size to receive a five-cent piece, the chute 11 and slot 7' are of a size to receive a ten-cent piece, and the chute 12 and slot 8' are of a size to accommodate a twenty-five-cent piece.

The outer end of the shaft 3 is provided with a handle 13 whereby the shaft and with it the drums 6, 7 and 8 may be rotated in the bearings 2 and 4 as hereinafter set forth more in detail.

14, 15, 16, 17 and 18 represent a plurality of horizontal levers, pivoted at predetermined points intermediate their ends to suitable supports, the short arm of each of said levers being free and terminating at a point substantially adjacent one of the drums on the shaft 3 with its forward edge in close proximity and lying just behind the coin slot in said drum, whereby when a suitable coin is deposited in the coin slot, and the drum rotated by the shaft 3, said coin will engage the short arm of the respective lever. In the interest of clarity, in Figs. 1 and 2 I have shown the mechanism broken away with only fragments of the levers 16 and 17, it being understood that any number of levers and drums may be employed as desired to suit various conditions. Furthermore, I have only shown pivotal supports for levers 14, 15 and 18, said supports being designated as 14', 15' and 18'. As shown in the drawings, the lever 14 is arranged to cooperate with the drum 6, the lever 15 with the drum 7, and the lever 18 with the drum 8.

All of the levers 14, 15, 16, 17 and 18 are arranged in superposed relation and spaced apart in such a manner as to avoid interference in operation so that any one of the levers may be independently operated on its pivot irrespective of the others. The opposite end of each lever terminates immedi-

ately behind one of a series of packages A to G inclusive, to be vended, and forms a delivery arm 14a, 15a, 16a, 17a and 18a respectively.

5 The articles or packages to be vended are carried in a delivery chamber, the front face of which is provided with a series of shutters or closures 20, 21, 22, 23 and 24, each of which is pivotally mounted at the lower extremity 10 of the closure next above, the uppermost closure 24 being pivoted to the front wall of the housing 1, any suitable mechanism being employed to return said closure to normal position after an article or articles have been 15 vended.

At the rear extremity of each delivery arm I provide a horizontal wing or shelf 14b, 15b, 16b, 17b and 18b respectively, the purpose of which is to engage beneath and support the package next above that being vended, as the delivery arm swings on its pivot and until such time as said delivery arm is returned to normal position by suitable springs 29. The wing then slides from beneath the column of 20 articles and permits the same to descend in the delivery chamber and replace the vended article or articles.

Each of the wings aforementioned, with the exception of 14b, carries a rigid depending arm 25, 26, 27 and 28 respectively, said arms being arranged in series and slidably engaging substantially arcuate slots in each of the wings below, the wing 18b or the uppermost wing having a solid surface. These 25 depending arms extend downwardly to a point below the lowermost delivery arm 14a and when any one of said delivery arms is swung on its pivot, the rigid depending arm carried thereby actuates all of the delivery arms arranged below as hereinafter set forth.

Having thus described the construction and arrangement of parts of my improved vending machine, its operation is as follows:—

25 We will assume that the articles in the delivery chamber are valued at five cents each and that the purchaser desires one article. He inserts a five-cent piece in the chute 10 which conducts the coin into the slot 6' in the drum 6 in the position shown in Figs. 1 and 2. The handle 13 is then rotated in clockwise direction which in turn causes the shaft 3 and drum 6 to rotate, the coin in the slot 6' engaging the short arm of the lever 14 and 30 swinging said lever on its pivot, thus causing the long arm or delivery arm 14a to force the lowermost article A from the delivery chamber through the pivoted closure 20 on to a platform or other suitable receptacle.

Now assuming that the purchaser desires to obtain two articles with one operation, he inserts a ten-cent piece in the chute 11, said coin engaging the slot 7' in the drum 7. 35 Thus when the handle 13 is rotated, the

lever 15 swings on its pivot and not only delivers article B, but through the medium of the depending arm 25, causes both delivery arms 14a and 15a to engage the respective articles A and B and vend the same through 70 the closures 20 and 21.

From the above it will be obvious that any number of articles may be delivered from the vending machine in a single operation, by the insertion of the proper coin or coins, it being understood that while I have shown an arrangement whereby a single coin actuates the delivery arms, the structure may be such that two or more coins inserted in the coin slots in the drums are necessary to engage the short arm of the levers. For example, in vending three articles, a five-cent piece and a ten-cent piece would have to be inserted in the chute (not shown) which controls the operation of the lever 16, in order to vend articles A, B and C. The principle of operation in all instances however, remains the same as above described.

After the drum has been rotated to a point where the coin carried thereby has passed the short arm of the respective lever, the continued rotation of said drum permits said coin to drop out of the slot and be deposited by gravity in a suitable coin receptacle, and the lever is returned to its normal position by means of springs 29, one end of each of which is secured to the respective levers, and the other end rigidly secured to points in the housing.

It is obvious that if the handle 13 is turned when there is no coin in any of the drums, said drums will rotate freely without actuating the delivery arms.

From the foregoing it is believed that the construction and advantages of my improved vending machine may be readily understood by those skilled in the art without further description, it being borne in mind that numerous changes may be made in the details disclosed without departing from the spirit of the invention as set forth in the following claims.

What I claim and desire to secure by Letters Patent is:—

1. In a vending machine, a rotary member, means on said member for receiving and firmly supporting a coin in projecting relation thereto, means for rotating said member, a fulcrumed lever arranged adjacent said rotary member with one arm in close proximity to said coin supporting means and lying in a plane parallel to the axis of said rotary member, said arm being adapted to be operatively engaged by a projecting coin upon the rotation of said rotary member, the other end of said lever forming an article delivery arm.

2. In a vending machine, a plurality of rotary members, means on each of said members for receiving and firmly supporting a coin in projecting relation thereto, means for

rotating said members, a fulcrumed lever arranged adjacent each of said rotary members with one arm in close proximity to the respective coin supporting means and lying in a plane parallel to the axis of the respective rotary member, said arm being adapted to be operatively engaged by a projecting coin therein upon the rotation of said rotary members, the other end of each of said levers forming an article delivery arm, and means carried by certain of said delivery arms for actuating certain other of said delivery arms to vend a plurality of articles in a single operation.

15 3. In a vending machine, a plurality of coaxial rotary members, means on each of said members for receiving and firmly supporting a coin in projecting relation thereto, means for rotating said members, a lever arranged adjacent each of said rotary members and fulcrumed on an axis transverse to the axis of said members with one arm in close proximity to the respective coin supporting means, and adapted to be operatively engaged 20 by a projecting coin therein upon the rotation of said rotary members, the other end of each of said levers forming an article delivery arm, and means carried by certain of said delivery arms for actuating certain other of said delivery arms to vend a plurality of articles in a single operation.

4. In a vending machine, a plurality of coaxial coin receiving cylinders of different diameters rotatably mounted in said machine and adapted to rotate idly in the absence of a coin, means in the periphery of each of said cylinders for receiving and firmly supporting a coin in projecting relation to said periphery, a plurality of levers arranged in superposed relation and fulcrumed on axes transverse to the axis of said cylinders with one end of each lever adjacent the periphery of one of said cylinders, the other end of each lever forming an article delivery arm, and means for rotating said cylinders, one of said cylinders cooperating with the respective lever through the medium of a projecting coin to deliver a single article, the other cylinders cooperating with their respective levers through the medium of projecting coins to deliver a plurality of articles from said machine.

5. Apparatus as claimed in claim 4 wherein the lowermost lever is adapted to deliver a single article, each of said other levers being provided with means for actuating the lever next below for delivering a plurality of articles.

6. Apparatus as claimed in claim 4 wherein the lowermost lever is adapted to deliver a single article, each of said other levers being provided with a depending arm adapted to engage and actuate the lever next below for delivering a plurality of articles.

65 7. Apparatus as claimed in claim 4 where-

in the lowermost lever is adapted to deliver a single article, each of said other levers being provided with means for actuating the lever next below for delivering a plurality of articles, the delivery arm of each lever carrying means for supporting the article next above during the delivery of said first named article or articles.

In testimony whereof I have affixed my signature.

CHARLES WALKER.
